UNITED STATES PATENT OFFICE.

ARTHUR JOSEPH DALEY, OF CONCORD, NEAR SYDNEY, NEW SOUTH WALES,
AUSTRALIA.

GROUND LINE MARKER.

Application filed January 30, 1924. Serial No. 689,437.

To all whom it may concern:

Be it known that I, ARTHUR JOSEPH DALEY, a subject of the King of Great Britain, residing at Park Avenue, Concord, near 5 Sidney, in the State of New South Wales and Commonwealth of Australia, sheet-metal worker, have invented a new and useful Improved Ground Line Marker, of which the following is a specification.

10 This invention relates to an improved ground line-marker that is to say a machine for marking lines upon flat surfaces and though devised for ground courts and bases for games generally it will be found 15 of especial utility for hard courts for tennis and also for wherever long distinct lines are required to be shown on the ground and on floors and other extensive flat surfaces. And this improved ground line-marker is 20 of simple and durable construction facile and effective in operation and as well comparatively cheap in first cost in maintenance and in use.

This improved ground line-marker has a 25 wheeled frame or carriage with the rear wheels close to a container and with the fore wheels extended forwardly medially and set a little farther apart than the width of the line to be marked and so that they 30 and the ground through the space between them will be in view of the operator. The container is open-topped and more or less arcuate at bottom and is divided by a perforated vertical diaphragm. There is an 35 oscillating agitator in one compartment and there is an oscillating mixer or brush in the other compartment both operably connected to the wheels. And from the container bottom is an outlet (with a regulatable valve) to a hinged launder underneath 40 having a nozzle or liner brush and this launder has convenient control devices for raising and lowering its nozzle end and has connection to the container outlet valve.

45 This invention is carried into practical effect by means of the improved ground line-marker preferably constructed as now described with reference to the drawings accompanying and forming part of this complete specification.

Figs. 1, 2 and 3 are respectively a side elevation a medial longitudinal elevation and a plan of this improved ground line-marker while Figs. 4, 5, 6 and 7 are details of 65 same.

The carriage having side members 8 inwardly set at the fore end 9 has front and rear axles 10 and 11 respectively mounted whereon are a couple of free wheels 12 and 12^a and each wheel has a scraper or 65 cleaner 13 affixed to the side members 8. The container 14^a is bolted to the side members and its arcuate one piece ends and bottom 14 is joined to side walls 15 sloping very slightly outwardly and has its rear 65 inwardly flanged to form splash guard 16. The perforated diaphragm 17 forms the container into two compartments 18 and 19.

A shaft 20 transversely about centrally across the container has bearings 21 at the 70 side walls 15 and at one end is bent to form a crank 22 which crank 22 is connected by rod 23 to a crank pin 24 on one of the wheels 12^a. A radial arm 25 fast to the shaft 20 carries a brush 26 and another radial arm 27 set or bent to dip into compartment 19 carries on its end an agitator bar or blade 28 adapted to oscillate in compartment 19 but preferably in a withdrawable wire or like strainer 29 therein. In the 80 bottom 14 of the compartment 18 is an orifice 30 within the range of oscillation of the brush 26 and said orifice 30 has a valve 31 adapted to be operated as hereinafter described.

A launder 32 is hinged at 33 to the container 14^a and narrows from its hinged end 33 to a discharging end 34 having taper nose 35 whose top wall 36 has slot 37 therein and said launder has adjustably fast there- 85 to the stem of valve 31. The nozzle 38 of rubber or the like flexible material has an orifice 39 with parallel sides and overhang top so that its width is arbitrarily fixed and consequently that of the delivered mark- 90 ing fluid. This nozzle 38 is affixed to the launder end 34 by means of resilient holder 40 and wing nutted screw 41 whose square shank is fitted in the slot 37 of top wall 36. But if desired a U-shaped brush such as 95 42 may be substituted for the nozzle 38.

A propelling hand bar 43 having cross bar 45 of inverted U-shape is bolted to the container walls 15. A control rod 44 from the discharge end 34 of the launder 32 100 passes through the hand bar 45 and has outwardly thereof a spring 46 below a tension nut 47 screwed on it as also preferably is a push nob 48.

In use the launder 32 is kept normally in 110

elevated inoperative position by spring 46 whose tension is set and regulated by nut 47 and in this position the valve 31 is closed tightly on the orifice 30. When the machine 5 is being propelled so as to mark the ground say a tennis court, revolution of the draught wheels 12 and 12^a with consequent movement of the crank 22 causes the agitator 28 and the brush 26 to be oscillated in the 10 respective compartments 18 and 19. The strainer 29 is charged with a powder as say lime and the compartments 18 and 19 with water and thus the fluid and the lime commingle and the oscillating agitator 28 compels 15 a thorough mixing and no escape of large particles into compartment 18 can occur. In the latter compartment oscillating brush 26 keeps the fluid stirred and flowable and the outlet orifice 30 clear. The position of 20 the nozzle 38 in relation to the court and the amount of marking fluid flowing through said orifice 30 and launder 32 is governed by depression of the control rod 44 to the limit allowed by the adjusting nut 47 while the 25 track to be marked is easily followed by keeping the front wheels 12 one on either side of a guiding line or thread.

On releasing the control rod 44 the spring 46 raises the launder 32 and the valve 31 30 closes the orifice 30 cutting off the discharge of the marking fluid.

What I claim as my invention and desire to secure by Letters Patent is:—

1. An improved ground line-marker comprising a carriage, a container thereon having two compartments, one of said compartments having an outlet, an agitating device, and a mixing device operable by the draught wheels for mixing and 35 agitating powder and fluid, said mixing device movable over said outlet, and combined therewith an under launder having devices for adjusting its inclination having 40 a discharge end and nozzle having control devices for raising and lowering itself and having devices for regulating a flow of the contents from said container on adjustment of the inclination of said launder as and for 45 the purposes set forth substantially as herein described and explained.

2. In and for improved ground line-marker the combination with a container divided into two compartments by a perforated diaphragm, of an oscillating agitator 50 operably connected to a crank on one of the draught wheels in one compartment and oscillating brush mixer in the other compartment operably connected to a crank on one of the draught wheels an outlet 55 orifice in the track of the brush mixer and

devices for permitting and directing a discharge from said container and devices for aligning on the ground said discharge as and for the purposes set forth substantially as herein described and explained. 65

3. In and for an improved ground line-marker the combination with a carriage supporting a container and having the front wheels set apart the width of the desired marking line of devices for mixing and 70 agitating water and powder in said container a hinged launder having a tapered slotted nose and a flexible nozzle a flexible holder for said nozzle an outlet orifice in said container with valve a connection 75 between said valve and said hinged launder and control devices for raising and lowering said launder and operating said valve as and for the purposes set forth substantially as herein described and explained.

4. In and for improved ground line-marker the combination with carriage having side members 8 front axle 10 rear axle 11 wheels 12 and 12^a of a container having one piece ends and bottom 14 side walls 15 80 perforated diaphragm 17 discharge orifice 30 an under hinged launder 32 having connection to said valve 31 and devices for raising and lowering the nozzle end of said launder 32 as and for the purposes set forth 90 substantially as herein described and explained and as illustrated in the drawings.

5. In and for improved ground line-marker the combination with a carriage and a container having compartments 18 and 19 95 of a crank shaft 20—22 connecting rod 23 crank pin 24 radial arms 25 and 27 carrying brush 26 and agitator 28 respectively discharge orifice 30 with valve 31 and a launder 32 connecting to the said valve 31 as and for the purposes set forth substantially as herein described and explained and as illustrated in the drawings.

6. In and for improved ground line-marker the combination with a wheeled container having a discharge orifice 30 with valve 31 of a hinged launder 32 having a discharge end 34 taper nose 35 a flexible nozzle 38 having holder 40 and control devices for operating said launder substantially as herein described and explained and as illustrated in the drawings. 105

In testimony whereof I have signed my name to this specification in the presence of two subscribing witnesses.
